CLAIM

The ornamental design for a tire, as shown and described.

DESCRIPTION

FIG. 1 is a front view of the tire showing the new design; FIG. 2 is a rear view thereof;

FIG. 3 is a partial enlarged front view taken from FIG. 1;

FIG. 4 is a front perspective view thereof;

FIG. 5 is a top view thereof; and,

FIG. 6 is a left-side view thereof.

The broken lines in the drawings used for demarcation of enlarged portions of the tire form no part of the claimed design.
